UNITED STATES PATENT OFFICE.

CHARLES F. SPAULDING, OF ST. JOHNSBURY, VERMONT.

IMPROVED CLOTHES-WRINGER.

Specification forming part of Letters Patent No. 42,607, dated May 3, 1864.

To all whom it may concern:

Be it known that I, CHARLES F. SPAULDING, a resident of St. Johnsbury, in the county of Caledonia and State of Vermont, have invented an Improved Clothes Wringing and Squeezing Machine; and I do hereby declare the same to be fully described in the following specification and represented in the accompanying drawings, of which—

Figure 1 denotes a front elevation, Fig. 2 an end view, and Fig. 3 a vertical and longitudinal section, of it. Fig. 4 is an inner side view of one of slotted guards. Fig. 5 is an inner side view of one of the end portions of the frame.

The nature of my invention consists in the combination of eccentric guides or cams with the expressing-rollers and their supporting-frame, the said guides being for the purpose or object as hereinafter set forth; also, in the combination of certain slotted guards with the rollers, the eccentric guides, and the frame; also, in the arrangement and combination of elastic springs with the eccentric guides and the rollers, the springs and guides by their co-operation serving to produce friction on the rollers while they may be in the process of expressing a liquid from clothing or an article which may be in the act of being run between them.

The frame of the machine is composed of two end parts, A A', united by a cross-bar or rod, B. Two elastic rollers, C D, are disposed within the said frame in manner as represented in the drawings. The shaft *a* of the lower of these rollers is supported within and by boxes *b*, each of which is arranged within one of the end portions, A A', of the frame, and is so applied thereto as to be capable of sliding vertically therein. Each of the said boxes is supported on a vulcanized india-rubber spring, *c*, or on a metallic cap, *d*, placed on the top of the spring.

The springs *c* rest on the bottoms of openings *e*, made within the end portions, A A', of the frame, each of the springs having the form as represented in Fig. 5. The upper part, *h*, of each of the said openings constitutes not only a bearing but an eccentric guide for one of the journals *ff* of the upper roller, C, the said part *h* being curved eccentrically relatively to the axis of the lower roller, and ar-

ranged in manner as represented in the drawings. There are two elongated metallic caps or guards, G G, applied to the set of rollers, each guard being arranged within the frame and made to cover the next two adjacent ends of the two rollers or lie against them or lap over the curved surfaces of the rollers, as shown in the drawings. Each of these guards, besides having a circular hole, *g*, made through it for the reception of the shaft of the upper roller, C, has an elongated slot, *k*, for reception of the shaft of the lower roller, D, such slot being necessary to enable the rollers to either approach toward or depart from one another as circumstances may require.

A clamp, E, provided with a screw, *i*, and a nut, F, is applied to each of the two parts, A A', of the frame, and serves therewith to confine the machine to a wash-tub.

A crank being fixed on the shaft of the lower roller, if such shaft be revolved in one direction by manual power applied to the crank, not only will the two rollers be put in revolution, but, in consequence of the journals of the upper roller being rolled against the eccentric guides *h h*, the said roller will be moved forward on the lower roller and pressed toward it in such manner as to cause the axis of the upper roller to approach that of the lower one.

On reversing the motion of the crank the upper roller will be caused to fall back and its axis depart from that of the lower one. The object, therefore, of the eccentric guides *h h* is not only to aid in producing the necessary pressure of the rollers on the clothes during the process of expressing liquid therefrom, but subsequently to relieve the rollers from the pressure against one another, the latter being accomplished by reversing the rotary motion of the crank. The slots *k k* of the cap-guards G G enable the latter to move with the upper roller during its movements toward and away from the lower roller. These guards serve not only to protect the journals of the rollers from the liquid expressed from the clothes, but to prevent the clothes from being wound around the journals.

I do not claim the invention of elastic rollers, nor do I claim, separately from the eccentric guides, the application of elastic springs

to the bearings of pressure-rollers, such application being common in wringing-machines.

I claim as my invention—

1. The combination of the eccentric guides *h h* with the rollers *C D* and their supporting-frame, the whole being so arranged as to enable or cause the rollers to operate, substantially as hereinbefore explained.

2. The combination of the slotted guards *G G* with the rollers *C D*, the eccentric guides

h h, and the supporting-frame, the whole being arranged as specified.

3. The arrangement and combination of the elastic springs *c c*, the eccentric guides *h h*, and the rollers *C D*.

CHAS. F. SPAULDING.
